[57] ABSTRACT

A dual function wrench including two work-engaging members cooperatively joined to enable selectively individual rotative application of torque or alternatively conjoint interengaged application of torque to different sections of a single piece of work.

DUAL FUNCTION WRENCH

FIELD OF THE INVENTION

The present invention relates generally to wrenches and more particularly to a wrench having two or more cooperative work-engaging sections so as to be capable of performing different functions.

BACKGROUND OF THE INVENTION

A number of wrenches are used for the installation and operation of "rough" plumbing pipes and fixtures as well as "finish" plumbing wherein valves or other structures are installed within a residence or other building. Utilization of such conventional wrenches and other plumbing tools on finish plumbing such as chrome plated valve bodies and housings within a residence require utmost care to avoid scoring or otherwise marring the polished finish and renders the task tedious and frustrating, particularly when the installation or operation occurs within a confined space such as the enclosing cabinet beneath a bathroom sink. The problem is aggravated by the fact that initial installation of such a valve requires application of considerable torque and substantial torque is also required to open or close the valve after installation because of the fact that it is not frequently manipulated between its open and closed positions.

SUMMARY OF THE PRESENT INVENTION

Accordingly, it is the general objective of the present invention to provide a specialized wrench which incorporates two or more work-engaging sections that can be utilized separately or in cooperation to enable performance of different plumbing operations, such as, for example, the installation and operation of a valve without deleterious effects on its exposed, finished surfaces. Generally, one of the work-engaging sections or members is designed to function separately to perform one function. In the case of a valve including a valve body or housing, and an operatively attached handle, the single work-engaging member can constitute a socket or other structure arranged to engage the handle so that application of torque to the wrench section will facilitate opening or closing of the valve. A second work-engaging member is conjoined with the first in a non-cooperative disposition during such operation of the valve so as not to interfere but is capable of connective interengagement with the first work-engaging member so that when torque is applied to the first, it simultaneously is applied to the second work-engaging member and the two members then function in concert for a different function. In the specific case of the valve, this second work-engaging member can take the form of a pair of fixed jaws designed to encompass and operatively engage the valve body so that application of torque will effect rotation of the valve body in unison with the handle thus to facilitate easy installation of the valve on a projecting, threaded pipe. Preferably, the lateral dimensions of both work-engaging members are maintained at a minimum and an axial drive socket is provided in the first work-engaging member to facilitate application of the torque to the unit by the conventional drive member of an ordinary socket set, thus permitting the application of torque in the installation of a valve or other fixture in a relatively confined space.

BRIEF DESCRIPTION OF THE DRAWINGS

The stated objective of the invention and the manner in which it is achieved as summarized hereinabove, will be more readily understood by a perusal of the following detailed description of the exemplary embodiment of the invention as illustrated in the accompanying drawing wherein:

FIG. 1 is a perspective view of a dual-function wrench in operative position for the turning of a standard valve handle, the latter being indicated in phantom lines,

FIG. 2 is an elevational view of the wrench as viewed from the right of FIG. 1, and

FIG. 3 is a perspective view generally similar to FIG. 1 but showing the dual functioning of the wrench sections in cooperative relationship for the installation of a valve, the latter being again shown in phantom lines.

DETAILED DESCRIPTION OF THE EXEMPLARY EMBODIMENT OF THE INVENTION

With initial reference to FIG. 1, the first work-engaging member 10 specifically includes an elliptical socket 12 integrally formed at one end of a cylindrical shank 14. This socket 12 is arranged to closely encompass an elliptical valve handle indicated at H in FIG. 1 to enable the application of torque to turn the handle in a manner so that no relative slippage occurs, thus to eliminate any marring of the handle surfaces. With additional reference to FIG. 2, a rectangular socket 16 is formed at the opposite end of the shank 14 for reception of a conventional drive member (not shown) of a socket set although, as will be apparent, the elliptical socket 12 can have a different configuration for the application of torque to different valve handles, and, in turn, different torque-applying means can be arranged on the shank 14.

The second work-engaging member 20 includes a pair of fixed jaws 22 that project in parallelism from the end of a rigid metal strap 24 whose opposite extremity is pivotally mounted on a pivot pin 26 attached exteriorly of a metal ring 28 that loosely encompasses the shank 14 of the first work-engaging member 10, thus allowing turning of such first work-engaging member, for example, when operating a handle as illustrated in FIG. 1, without any corresponding rotation of the second work-engaging member 20. The ring 28 which mounts the second work-engaging member in addition to allowing the relative rotation of the two members 10, 20 also permits limited axial sliding motion, limited by the socket 12 at one end of the shank 14 and by small lateral protuberances 18 adjacent the drive end thereof.

In order to allow the cooperative functioning of the elliptical socket 12 and the fixed jaws 22, for example, in the installation of the valve V as generally illustrated in FIG. 3, cooperative interengagable elements are formed on the first and second work-engaging members 10, 20, and, as specifically shown, include a pair of rebent flanges 30 on the exterior of the socket 12 of the first work-engaging member 10 that form slots that are capable of receiving rigid ears 34 projecting laterally from the sides of the rigid strap 24 of the second work-engaging member. Initially, the second work-engaging member 20 is pivoted upwardly from its FIG. 2 disposition so as to lie in substantial parallelism with the first work-engaging member 10 and then is shifted

axially to bring the lateral ears 34 into the slots, the 5
slidable and rotatable mounting of the ring 28 permitting such interconnection to be established. In such interconnected position, the centers of the jaws 22 and the socket 12 are axially aligned, and any torque applied to the first work-engaging member 10 through for example, utilization of the drive member of the socket set, is, in turn, transferred to the second work-engaging member 20 and the two rotate in unison. When applied to the installation of a valve, as indicated in FIG. 3, the elliptical socket member 12 is in engagement with the valve handle H and the fixed jaws 22, in turn, operatively encompass a hexagonal portion of the valve body so that rotation is imparted to the entire valve V for its threaded application to the end of a threaded pipe. 15 Again, close encompassment of both engaged sections of the valve V is achieved so that the installation can occur rapidly without marring the exterior surfaces of the valve.

As has been indicated throughout the foregoing description, many modifications and/or alterations in the configuration of the work-engaging members and their cooperative interengaging elements can be made without departing from the spirit of the present invention; and accordingly, the actual scope of the invention is to 25 be indicated only by reference to the appended claims.

What is claimed is:

1. A dual-function wrench which comprises
a first work-engaging member,

10
a second work-engaging member, and
means including cooperative interengagable elements on said first and second work-engaging members for connecting said members for conjoint operation in unison, said first and second work-engaging members being disposed in axial alignment when connected by said interengagable elements.

2. A dual-function wrench according to claim 1

15
wherein

said first work-engaging member forms an elliptical work-encompassing socket.

3. A dual-function wrench according to claim 1
wherein

said second work-engaging member includes a pair of fixed jaws.

4. A dual-function wrench according to claim 1
wherein

said work-engaging members are connected for relative axial and rotative motion when said members are not connected by said interengagable elements.

5. A dual-function wrench according to claim 4
wherein

said connecting means includes means forming a slot on one of said members and an ear on the other of said members to enable interconnection upon pre-established relative axial motion of said two work-engaging members.
